CLAIM

The ornamental design for a broom-style cleaning appliance, as shown and described.

DESCRIPTION

A portion of the disclosure of this patent document contains material which is subject to copyright protection. The copyright owner has no objection to the facsimile reproduction by any one of the patent document or the patent disclosure, as it appears in the Patent and Trademark Office patent file or records, but otherwise reserves all copyright rights whatsoever.

FIG. 1 is an enlarged front perspective view of head of the broom-style appliance;

FIG. 2 is an enlarged rear perspective view thereof;

FIG. 3 is a front view of the broom-style cleaning appliance;

FIG. 4 is a rear view thereof;

FIG. 5 is a top view thereof; and,

FIG. 6 is a bottom view thereof.

The broken line circles in the figures depict areas of the broom-style cleaning appliance that are enlarged and form no part of the claimed design. All other broken lines in the figures depict portions of the broom-style cleaning appliance that form no part of the claimed design.
